UNITED STATES PATENT OFFICE

2,077,689

KNIFE SHARPENER

Julius A. Grobstein, Chicago, Ill.

Application March 4, 1935, Serial No. 9,168

23 Claims. (Cl. 51—114)

My invention relates to an improved method and means for sharpening knives, particularly knives employed by furriers.

In the fur industries, it is customary in making fur garments and the like to cut the fur skins sometimes into relatively small pieces for the purpose not only of fitting the garment, but also for the purpose of matching the fur as to color, texture, and the like. A fur cutter, therefore, will work for long periods at a time cutting skins with a specially designed hand fur knife well known in the industry. On account of the extensive use to which the knife is put, it requires frequent sharpening. Heretofore, no suitable means for sharpening these knives has been known except a small stone which the cutter employs by hand, and a leather hone for finishing the edge. Not only does this hand sharpening require a considerable part of the furrier's time, but very few cutters have the ability to produce a good edge and the use of a knife which is improperly sharpened further complicates the work.

The object of my invention is the provision of an inexpensive sharpening tool specially adapted for applying a fine cutting edge to the usual type of fur knife.

Another object is the provision of an inexpensive instrument which may be adapted for sharpening other types of knives such as detachable blades sometimes employed in furrier's knives.

Another object is the provision of means for pointing fur knives and similar knives.

Other objects and features of my invention will be apparent from the following description taken with the accompanying drawings, wherein

Fig. 1 is a transverse sectional view of one embodiment of my invention, some of the parts being in elevation, the view being taken substantially along the line 1—1 of Fig. 2, looking in the direction of the arrows;

Fig. 2 is a longitudinal sectional view showing some of the parts in elevation;

Fig. 3 is a plan view, partly in section;

Fig. 4 is a fragmentary plan view showing the sharpening elements;

Fig. 5 is an enlarged fragmentary sectional view partly in elevation taken on the line 5—5 of Fig. 3, but showing the parts in modified position;

Figs. 6 and 7 show modified types of knives employed by furriers; and

Fig. 8 shows an adapter for use when sharpening such blades as those shown in Figs. 6 and 7.

According to the general provisions of my invention, I provide a movable carriage adapted to receive a fur knife, so arranged that when the fur knife is in position and the motor operated, the carriage will advance and carry the knife along a predetermined path in contact with a pair of sharpening elements of special design. The sharpening elements are of a composite type in the form of a pair of co-acting wheels of special shape provided with a plurality of stone sharpening sections and co-acting leather stropping sections. The knife and sharpening members are so disposed with respect to each other that the stone portions first engage the knife edge while moving in a generally downward direction, and the stropping portion, preferably made of leather thereafter engages the portion of the blade which the stone portions have engaged to finish the sharpening action. The mechanism is designed so that when the knife has moved along its predetermined path and all portions of the edge have been sharpened, the operating mechanism is automatically stopped, and the knife and carriage are returned to the starting position and the knife is readily removed for use.

Referring now to the drawings, I show a frame comprising a main base plate 10, end plates 11 and 12, and side plates 13 and 14. Base plate 10 extends beyond the end plate 12 and a detachable angle plate 16 is provided, affording a housing for a driving motor 17 (Fig. 3). The driving motor has a shaft 18 extending from both ends thereof carrying a pair of bevel gears 19 and 21 meshing with bevel gears 22 and 23, respectively. These two bevel gears are pinned to shafts 24 and 26, journaled in end plate 12, and carrying bevel gears 27 and 28 meshing with gears 31 and 29 on shafts 33 and 32, respectively. It is these two shafts which drive the sharpening members adjustably carried thereon in a manner to be described.

Secured to base plate 10 are a pair of uprights 34 and 36 in which the shafts 32 and 33 respectively are journaled. These shafts carry sharpening members 37 and 38, each having a composite construction which will be described. For convenience, the support for the sharpening member 38 will be described first, the construction being the same in each case.

Shaft 33 has a non-circular portion 33a provided with a sleeve 39. The sharpening member 38 is secured on a threaded portion of the sleeve between nuts 41 and 42, a washer 43 being provided. Sleeve 39 has a flange 44 and a compression spring 46 is disposed around the sleeve and

engages between the flange 44 and an adjusting member 47. The second spring 48 is compressed between the adjusting member 47 and the nut 42. The adjusting member 47 is pivoted at 49 and a spring 51 urges the adjusting member in a clockwise direction around its pivot, looking at Fig. 1. An adjusting rod 52 has a nut 53 intermediate its ends on a threaded portion, and the end thereof extends into an adjusting member 10 complementary to and co-acting with the adjusting member 47. The end of the rod 52 is shaped to receive a suitable tool to permit turning.

The knife to be sharpened is indicated by the character 54, and this knife is supported between 15 sharpening members on a carriage which progresses it longitudinally to present all portions thereof to the sharpening members. The manner in which this knife is supported will now be described.

20 The top of the machine comprises a cover plate 56, the center of which is recessed longitudinally of the machine to receive a slideable carriage 57. Within the carriage is an adapter 58 adapted to hold the knife 54, or to support a modified form 25 of knife, as will be described later. At the top of the carriage are a pair of brackets 59 and 61 in which are journaled the ends of a general U-shaped rod 62, to the middle portion of which is attached a block 63 carrying a handle 64. The 30 U-shaped rod 62 is provided with a spring 66 which normally tends to hold the rod and handle in an upright position, as shown in Fig. 5.

At one end of the rod, the carriage is provided with a pair of brackets 67 in which is journaled 35 a pin 68 carrying a latch 69, in the form of a bell crank lever. This bell crank lever has an upper portion 69a and a lower portion 69b. A spring provided on the pin 68 moves the bell crank lever in a counter-clockwise direction, looking at Fig. 2. The end of the U-shaped rod 62 is slotted so that when it is moved to the position shown in Fig. 1, the upper portion 69a of the latch engages in the slot and prevents the return of the handle to the upper position. The manner 45 in which this latch is released will be described in a later portion of the specification.

The lower portion of the carriage 57 is provided with a plurality of brackets 71 and 72 through which rods 73 and 74 extend, and on 50 which rods the carriage is adapted to move when propelled by means which will be described hereinafter. The ends of the rods are generally U-shaped and are fulcrumed in brackets 76 supported on the under side of the cover plate 56. Looking at Fig. 2, spring 77 tends to move the rods in such a direction as to hold the carriage 55 57 in a downward position. The rods also have collars 78 which are engaged by one end of springs 79 extending around the rods. The other 60 end of the springs 79 engage followers 81 provided on the carriage.

As shown in Fig. 5, the carriage 57 is provided with wells in which compression springs 82 are placed, one end of the springs engaging the bottom of the wells and the other end engaging pins 83 which extend up and are adapted to be engaged by the adapter 52. When the handle 64 is pressed down, the springs 82 are compressed, but on release of the handle they expand and cause 70 the adapter to spring upwardly so that it is easily removed.

For removing the knife shown at 84 from the adapter (Fig. 1), I provide a pair of springs 86 which are set in recesses on opposite sides of the 75 adapter and engage along the tapered sides of

the knife. When pressure is removed from the top of the knife, these springs cause the knife to be forced upwardly a sufficient distance to permit the fingers to grasp a relatively wide portion of the knife indicated at 86a.

Although the knife is in general provided with sufficient support by the carriage, I provide an additional centering means in the form of a pair of grooved rollers 87 and 88 journaled on shafts 89 and 91 carried on uprights 92 and 93. These grooved rollers function to protect the edge of the knife and also to hold it more securely during the time that the leading and rear edges of the knife are in contact with the sharpening members.

I provide means for moving the carriage and knife carried thereby longitudinally of the machine during the sharpening operation. The mechanism employed for this purpose is of such a character as to permit ready return of the carriage to the starting position when it is advanced to its extreme of travel. The specific embodiment which I show for securing this result is as follows:

Secured to shaft 24 is a worm 94. This worm 25 is adapted to engage a rack 96 carried by an arm 97 pivoted to the rod 74 but constrained to move with the carriage. This arm 97 has an offset 98 (Figs. 1 and 5), with a cam-like edge engaged by a roller 99 journaled in the end of a bell 30 crank lever 101. This bell crank lever is pivoted in the carriage at 102 and has one end adapted to be depressed by a pin 103 when the handle 64 is lowered. A spring 104 is interposed between the pin 103 and the bell crank lever 101 to allow 35 for difference in the adjustment of the parts. A spring 106 is attached to the carriage and to the arm 97, normally tending to hold the rack 96 out of engagement with the worm 94.

The motor 17 is controlled by a switch 107 provided with push buttons 108 and 109. Push button 108 is manually operated and can be reached from the outside of the machine. Push button 109 is in the path of arm 97. When the rack 96 reaches its limit of travel, push button 109 is 45 depressed and the motor is stopped.

The general structure of the sharpening members 37 and 38 should be clear from the drawings. In general, however, I provide a frame 38a, preferably formed of metal, a stone portion 50 38b, and a leather edge 38c. Elements 37a, 37b, and 37c represent similar parts on sharpening member 37. The relative size of the stone and leather may be modified, but as will be shown in the description of the operation of the machine, 55 each portion is able to perform its own function independently. It will be understood that in place of stone and leather, I may substitute other materials, the portion 38b being the sharpening portion and the portion 38c the stropping portion. It will be seen that there are three sharpening sections or lugs on each one of the sharpening members (see Fig. 2). These portions engage the knife successively, alternating between the two sharpening members. The use 60 65 of this arrangement permits placing the sharpening wheels at an angle to each other to produce the proper sharpening action.

At the end of motor shaft 18 and exteriorly 70 of the machine, I provide a sharpening stone 111. Adjacent the sharpening stone I provide a by-part knife holding frame 112 pivoted at 113 and provided with a handle 114. As shown in Fig. 3, the knife may be supported in such a manner as to re-point it should the point be broken off for 75

any reason. After the knife is repointed, it may have its edge sharpened by the mechanism previously described.

I provide suitable means for introducing oil or other fluid to the sharpening members to facilitate sharpening. As shown in Fig. 1, the bevel gear 28 meshes with a bevel gear 116 secured on an upright shaft 117. The lower portion of this shaft drives a pump, one gear of which is shown 10 at 118. Oil in suitable quantities is withdrawn from a sump and delivered through a pipe 119, whence it is fed to the knife at the point where the sharpening members engage it.

The operation of the machine is as follows: 15 The knife 84 is placed in position in the adapter and the handle moved downwardly to hold the adapter in position and to cause the rack 96 to engage the worm 94. The switch 108 is then pressed and the motor is operated and through 20 the gear mechanism described, drives the two sharpening members. These two sharpening members engage the knife in approximately the position indicated by the character A in Fig. 2, the sharpening members being rotated in the 25 direction indicated by the arrow. The knife immediately starts to move in the direction indicated by the arrow in Fig. 2 placed on the body of the knife. First one sharpening member engages one side of the knife and immediately 30 the other sharpening member engages the other side of the knife. As shown in Fig. 2, at the point of engagement, the sharpening surface first engages the knife with a generally downward but partly rotating and longitudinal movement, very 35 effective for sharpening purposes. As the knife moves along, the tip will engage the leather portion where this particular portion of the edge is stropped or finished. As the knife advances still further, it passes the point at which it is engaged 40 with the leather, and subsequently is engaged by the grooved roller 88 to protect the edge. In this way, the entire edge of the knife is subjected first to the grinding or sharpening action of the stone and then to the stropping or finishing action of 45 the leather.

On account of the support for the sharpening members, they adjust themselves readily to the position of the knife and the depth to which the knife extends down between them. When a 50 knife is new, it extends well down toward the lower portion of the sharpening surface, but as it becomes worn, it extends down less and less. Nevertheless, the sharpening members adjust themselves to this difference. Moreover, by 55 means of the adjusting rod 52 further adjustment can be made.

As the carriage moves to the right in Fig. 2, the spring 79 is tensioned until the portion 69b of the latch engages the end of rod 74. This 60 releases the latch, allowing the handle to rise and at the same time releasing the rack 96 from the worm 94. The arm 97 has in the meantime engaged the button 109 and stopped the motor. I adjust the position of the parts so that the motor 65 is stopped just before the latch is released, and enough movement will still take place to release the latch. As soon as the rack 96 is released from worm 94, the springs 79 return the carriage to starting position and the knife, having already 70 been released, can be removed.

In connection with the sharpening members, it is to be noted that they slant in two ways so as to accommodate the knife between them and sharpen the edge thereof on the down stroke.

75 The compound inclination of the two sharpening

members is understood by reference to Figs. 1 and 4.

In recent years, knives with removable blades have been offered to furriers. In general, they have substantially the same shape as the single piece knife, and if desired the entire knife, including holder and blade, may be placed in the sharpening machine. In Fig. 8, however, I show a modified adapter 121 formed in two parts and adapted to engage in the carriage 57. The blade 122 is suitably carried at the lower part of the adapter. The blade 122 is shown in Fig. 6. A somewhat modified blade employed also in fur knives is indicated by the character 123 in Fig. 7. By means of the adapter, a number of these blades may be sharpened at one time and be kept ready for insertion into the holder as the cutter needs them. Most cutters do not favor the knife with the removable blade and so I consider, as the main embodiment of my invention, the sharpening of the conventional type of single piece fur knife of the general character shown in Figs. 1 and 2.

What I claim as new and desire to protect by Letters Patent of the United States is:

1. In a machine for sharpening knives, a pair of shafts disposed generally end to end of each other, a pair of substantially radially faced sharpening members secured on said shafts, a plurality of composite sharpening surfaces on said sharpening members disposed on said faces of the sharpening members facing each other, and means for moving the knife, longitudinally of its cutting edge, between said sharpening members whereby to cause the same to engage the edge and sharpen the same, said composite sharpening surfaces comprising sharpening and stropping elements which serve to preliminarily sharpen the knife and then strop it.

2. A sharpening machine as defined in claim 1, wherein said sharpening surfaces on the sharpening members are spaced equidistantly from each other and staggered, whereby to cause the sharpening surfaces of the two members to engage the knife alternately.

3. A sharpening machine as defined in claim 1, wherein said sharpening surfaces on the sharpening members are spaced equidistantly from each other and staggered, whereby to cause the sharpening surfaces of the two members to engage the knife alternately, the faces of the sharpening members being inclined with respect to each other and the sharpening surfaces of one sharpening member engaging between the sharpening surfaces of the other sharpening member at one portion of their circumference, whereby to permit the knife to lie between the sharpening members at the opposite portion of the circumference so that the surfaces engage the knife with a generally downward movement.

4. In a machine for sharpening knives, a carriage, means for locking the knife in said carriage with the edge to be sharpened projecting downwardly therefrom, means for advancing said carriage longitudinally of the knife, a plurality of substantially radially disposed moving sharpening surfaces engaging the knife as it moves, and each sharpening surface having a composite sharpening and stropping element and positioned so that, as the knife advances, the stropping element engages the edge after the sharpening element, and means for returning the carriage to starting position when it has reached its extreme of travel.

5. In a machine for sharpening knives, a car-

- riage, means for supporting a knife in said carriage with its edge projecting therefrom, a rotatable worm, a rack carried by the carriage and adapted to be engaged by the worm, means to secure the knife in the carriage, said last-mentioned means serving to effect engagement of the rack and the worm, said carriage being moved longitudinally of the knife edge by the action of said worm and rack, and sharpening means engaging and sharpening the edge of the knife as the carriage advances.
6. In a machine for sharpening knives, a carriage, means for supporting a knife in said carriage with its edge projecting therefrom, a rotatable worm, a rack carried by the carriage and adapted to be engaged by the worm, means to secure the knife in the carriage, said last-mentioned means serving to effect engagement of the rack and the worm, said carriage being moved longitudinally of the knife edge by the action of said worm and rack, sharpening means engaging and sharpening the edge of the knife as the carriage advances, and means for releasing said rack and worm when the carriage reaches its extreme of travel.
7. In a machine for sharpening knives, a carriage, means for supporting a knife in said carriage with its edge projecting therefrom, a rotatable worm, a rack carried by the carriage and adapted to be engaged by the worm, means to secure the knife in the carriage, said last-mentioned means serving to effect engagement of the rack and the worm, said carriage being moved longitudinally of the knife edge by the action of said worm and rack, sharpening means engaging and sharpening the edge of the knife as the carriage advances, means for releasing said rack and worm when the carriage reaches its extreme of travel, and means for returning the carriage and releasing the knife.
8. In a machine for sharpening knives, means for supporting a knife, means for advancing the knife longitudinally of its cutting edge, a pair of co-acting substantially radially disposed sharpening members engaging the knife edge with a motion generally away from the edge, said members having a composite sharpening and stropping surface and positioned so that, as the knife advances, the stropping surface engages the edge after the sharpening surface.
9. In a knife sharpening machine, means for supporting a knife, a pair of shafts disposed generally end to end of each other, a rotatable substantially radially faced sharpening wheel fixed to each shaft, each of said wheels having spaced composite sharpening and stropping portions thereon, the spaced composite sharpening and stropping portions on one wheel being offset from those on the other wheel, and means providing relative movement, longitudinally of the cutting edge of the knife, between the knife supporting means and the rotatable sharpening wheels whereby the knife is initially sharpened and then stropped.
10. In a knife sharpening machine, means for supporting a knife, a pair of rotatable substantially radially faced sharpening wheels the axes of rotation of which are set at an angle to each other whereby at least the edge portion of the knife may fit in the resulting grooved space between said sharpening wheels, each of said wheels having spaced composite sharpening and stropping portions, the composite sharpening and stropping portions on one wheel being offset from those on the other wheel, and means for advanc-

ing the knife on its supporting means in a direction longitudinally of the cutting edge of the knife whereby the knife is initially sharpened and then stropped.

11. In a machine for sharpening knives, a pair of shafts disposed generally end to end of each other, a substantially radially faced sharpening member secured on each of said shafts, a plurality of spaced composite sharpening and stropping surfaces disposed on faces of the sharpening members facing each other, the spaced composite sharpening and stropping surfaces on said sharpening members being in staggered relation to each other, means to rotate the shafts and sharpening members, and means for moving the knife to be sharpened between said sharpening members whereby to cause the same to engage the cutting edge of the knife and sharpen the same, the sharpening and stropping surfaces being so arranged that the knife is initially sharpened and then stropped. 5 10 15 20

12. In a machine for sharpening knives, means for holding a knife, means for advancing the knife longitudinally of its edge, at least one grooved roller which serves to support the edge of the knife, and a pair of coacting sharpening members engaging the knife with a motion generally away from the edge, said members having a composite sharpening and stropping surface and positioned so that, as the knife advances, the stropping surface engages the edge after the sharpening surface. 25 30 35

13. In a knife sharpening machine, a pair of rotatable substantially radially faced sharpening wheels each of which is mounted on an individual shaft and the axes of rotation of said wheels being set at an angle to each other, each of said wheels having spaced composite sharpening and stropping portions thereon, the spaced composite sharpening and stropping portions on one wheel being offset from those on the other wheel whereby the knife is initially sharpened and then stropped. 40 45 50

14. A tool for sharpening knives comprising a body member of generally circular cross section, and a series of substantially radially disposed composite sharpening and stropping portions mounted thereon, said portions being spaced from each other. 45

15. A tool for sharpening knives comprising a body member of generally circular cross section and having a substantially flat surface, said surface being provided with a series of substantially radially disposed composite sharpening and stropping portions, the sharpening portions being peripherally inset from the stropping portions, said composite portions being spaced from each other. 50 55

16. The tool as defined in claim 15, wherein the stropping portion is formed of leather. 60

17. In a knife sharpening machine, flexibly mounted means for supporting a knife, a pair of rotatable sharpening wheels the axes of rotation of which are set at an angle to each other whereby a sharpening groove is formed therebetween, each of said wheels having spaced sharpening surfaces thereon which are in staggered relation to each other, and means for automatically adjusting the extent of the sharpening groove to accommodate knives of varying depth, said last mentioned means cooperating with the flexibly mounted knife supporting means to provide said automatic adjustment. 65 70 75

18. The machine as defined in claim 17, where- 75

in the last mentioned means includes spring means.

19. A method of sharpening knives which comprises advancing the knife longitudinally of its cutting edge and in only a single forward direction between two angularly disposed substantially radially faced composite sharpening and stropping surfaces, and rotating said surfaces while advancing the knife whereby both sharpening and stropping of the knife successively take place in the order named, the sharpening and stropping strokes being in a direction generally downward and away from the body of the knife.

20. A method of sharpening knives which comprises advancing the knife longitudinally of its cutting edge between two angularly disposed substantially radially faced sharpening members having spaced composite sharpening and stropping surfaces in staggered relation to each other, and rotating said members while advancing the knife whereby both sharpening and stropping of the knife successively take place in the order named, the sharpening and stropping strokes being in a direction generally downward and away from the body of the knife, and the opposite sides of the knife being alternately contacted with the composite sharpening and stropping surfaces.

21. A knife sharpening machine comprising a knife holder adapted to immovably clamp the knife blade therein and a plurality of substantially radially faced rotatable sharpening members which engage the edge of the knife to sharpen the same, said knife holder being flexibly mounted and automatically self-adjusting to correct the position of the knife as it wears away.

or knives of varying depths, with respect to the rotatable sharpening members, said sharpening members having composite sharpening and stropping portions whereby the knife is initially sharpened and then stropped.

22. In a machine for sharpening knives, means for supporting a knife, means for advancing the knife longitudinally of its edge, and a pair of coacting rotatable sharpening members, each having a plurality of composite sharpening surfaces staggered with respect to each other, the knife edge being adapted to be disposed between said surfaces, and each of said composite surfaces having a sharpening and stropping portion and positioned so that, as the knife advances, the stropping surfaces engage the edge after the sharpening surfaces, and a grooved roller forward of the rotatable sharpening members in the direction of advancement of the knife, said grooved roller serving to support and protect the edge of the sharpened knife from injury.

23. In a machine for sharpening knives, means for supporting a knife, means for advancing the knife longitudinally of its edge, a pair of coacting sharpening members engaging the knife edge with a motion generally away from the edge, said members having a composite sharpening and stropping surface and positioned so that, as the knife advances, the stropping surface engages the edge after the sharpening surface, said knife supporting means being automatically self-adjusting to correctly position the knife as it wears away, or knives of varying depths, with respect to the coacting sharpening members.

JULIUS A. GROBSTEIN. 35
